UNITED STATES PATENT OFFICE.

JAMES A. ANDERSON, OF NEW YORK, N. Y., ASSIGNOR, BY DIRECT AND MESNE ASSIGNMENTS, TO MONTAUK ENGINEERING COMPANY, OF NEW YORK, N. Y., A CORPORATION OF NEW YORK.

THRUST-BEARING.

No. 806,389.

Specification of Letters Patent.

Patented Dec. 5, 1905.

Application filed March 7, 1905. Serial No. 248,888.

To all whom it may concern:

Be it known that I, JAMES A. ANDERSON, a citizen of the United States, residing at New York, Manhattan borough, in the county and 5 State of New York, have invented certain new and useful Improvements in Thrust-Bearings, which improvements are fully set forth in the following specification.

This invention relates to improvements in 10 bearings for shafts disposed to sustain substantial end pressure in practice, such as the main shafts of power sea-going vessels, the same being commonly known as "thrust-bearings."

15 The object of this invention is to provide a thrust-bearing which shall be simple and comparatively inexpensive as regards construction, durable, efficient, and reliable in practical service, which shall embody features serving to maintain under pressure and 20 in conjunction with a revolving shaft subject to end pressure a film or body of lubricant, whereby friction resulting from the end pressure on said shaft shall be effectually overcome and the wearing effect between said 25 shaft and the bearing reduced to a minimum, and shall possess certain well-defined advantages over prior analogous constructions.

The invention consists in the novel disposition and relative arrangements of the parts 30 and devices made use of in the details of the general construction and in certain combinations whereby the attainment of the foregoing object is rendered practicable, all of 35 which will be more particularly hereinafter referred to and set forth in the appended claims.

The invention is clearly illustrated in the 40 accompanying drawings, wherein similar reference characters denote like parts throughout the several views, and as to said drawings—

Figure 1 is a side elevation of a thrust-bearing embodying my said improvements. 45 Fig. 2 is an end elevation thereof looking at the rear of the bearing proper. Fig. 3 is a detail sectional view along the line III III of Fig. 1. Fig. 4 is a central vertical longitudinal section of the automatic controlling-valve, the scale being enlarged. Fig. 5 is a bottom plan view of said controlling-valve.

In carrying out my invention I make use of

material, having a lubricant-compartment 2 and upstanding lugs 3 at the ends thereof. This 55 casing is anchored, as by means of bolts 4, in position for service, as in common practice.

5 designates the shaft to which the thrust-bearing is applied, said shaft being preferably the main driving-shaft of a steamship and 60 being adapted to carry at one end the propeller. As arranged in the drawings the propeller is to be secured to the end 6 of the shaft so that the thrust of the propeller or screw will be toward the right-hand end of the apparatus as arranged in Fig. 1. This shaft within the bearing-casing is provided with a series of annular thrust-rings 7, which are spaced a suitable distance apart to form the 65 annular channels 8. These thrust-rings are 70 preferably formed integral with the shaft; but it will of course be understood that they may be secured thereto in any suitable manner. These rings are so arranged on the shaft that they rotate within the lubricant or 75 oil compartment 2, as shown clearly in Fig. 1, and are of such diameter that their lower portions extend below the level of the oil in 80 said compartment. Fitting closely within the channels 8 are yokes 9, whose ends are bolted down to the bearing-casing by bolts 10. These yokes are each provided with depending arms 11, which extend below the horizontal center of the shaft, as shown in Fig. 3, in order to provide an extensive bearing-surface 85 for the thrust-rings. To secure these yokes rigidly in position to enable them to resist the thrust of the thrust-rings and to accurately adjust them to the channels between said rings, heavy horizontal longitudinally-extending bolts 12 are mounted in the lugs 3 of the casing, one of these bolts being arranged on each side of the shaft. The yokes 9 are formed with the recesses 13 to receive the bolts 12, and screwed on said bolts on each side of the yokes are nuts 14. By this means the yokes may be accurately adjusted on the bolts, and the bolts will take up the strain brought on the yokes and prevent any movement thereof.

Each yoke is provided at its top with an oil-cup 15, and leading down to a point within the diameter of the thrust-rings is a port 16. This port opens at its lower end into a semicircular oil-delivery port 17, which opens 100

side of the yoke—that is, on the side toward the propeller—said side of the ring being the one to take up the thrust of the propeller. As shown in Fig. 3, the ends of the said oil-delivery port 17 extend to a point slightly below the horizontal center of the shaft, so that said port provides a very ample supply of lubricant to the thrust-ring. Connected to the upper end of each of the ports 16 is a supply-pipe 18, whose upper end is connected to a valve-casing 19, each of said valve-casings being connected by a pipe 20 to the oil-supply pipe 21. Suitable valves 22 are provided to regulate the supply of oil to the pipes 20. One end of the supply-pipe 21 is connected to a pump 23, which is supplied with steam by a pipe 24. The oil-intake-pipe 25 of the pump is connected, as shown in Fig. 3, to the oil-compartment 2 of the bearing-casing. The other end of the supply-pipe 21 is connected by a pipe 26 to pressure-controller 27. This controller consists of an upper steam-cylinder 28 and a lower oil-receiving cylinder 29 considerably smaller in diameter than the steam-cylinder and to the bottom of which the pipe 26 is connected. Within the steam-cylinder 28 is mounted a piston 30, which is connected by a piston-rod 31 to a similar piston 32 within the oil-cylinder. In communication with the top of the steam-cylinder above the piston therein is a steam-supply pipe 33, the lower part of said cylinder between the two pistons being open to the atmosphere through a small pipe 34. Connected to the piston 30 is a valve-operating rod 35, which projects through the upper head of said cylinder 28 and is connected, by means of an arm 36, to a rock-shaft 37, said rock-shaft being connected by an arm 38 and rod 39 to a valve-arm 40 of a controller-valve 41 in the steam-supply pipe 24.

In each valve-casing 19 is mounted a needle-valve 42, which is adapted to normally close an inlet-port 43, said inlet-port being connected by passage 44 to the pipe 18. The needle-valve is normally held to its seat by means of a spring 45, mounted in a chamber 46 in the casing 19, said spring bearing against a collar 47, formed on the stem 48 of said valve within the chamber 46. To regulate and adjust the tension of the spring 45 on the valve 42, a plug 49 is screwed in the end of the casing 19 and is adapted to bear against the end of the spring. This plug is axially bored to furnish a guide for the stem 48 of the valve. The valve is provided with a rib 51, which slides in a corresponding groove in the casing to prevent the rotation of the valve. The chamber 46 is provided at its inner end with an annular chamber 52, which is connected at its lower end with an outlet-port 53 to permit of the escape from said chamber of the oil which may be forced along the valve-stem from the passage 44.

Connected to the passage 44 of each casing

19 is a pressure-gage 54, which is adapted to indicate the pressure of oil in pipe 18 and in the connected passages 44 and within the ports 16 and 17. By means of these gages the pressure of oil in each of the yokes may be determined at a glance.

Connected to each oil-cup 15 is a port 55, which at its lower end connects with a port 56, which leads oil to the rear side of each of the thrust-rings, as shown clearly in Fig. 1. Oil fed through these ports is not under pressure, as the rear face of the thrust-ring may be efficiently lubricated without the necessity of placing the oil under pressure.

To retain the oil between the rear side of the yokes and the forward side of the thrust-rings and to prevent it being forced readily therefrom, semicircular guards 57 are secured to the yokes and cover the greater portion of the joint between said yokes and the thrust-rings. These guards rest on the outer surface of the thrust-rings, and their lower ends extend down into the bearing-casing, as shown in Fig. 1, so that any oil that may be forced out between the thrust-rings and the yokes will be by these guides led back into the oil-compartment 2. The inner edges of these guides are arranged to bear closely on the thrust-rings. Similar guides 58 are arranged on the forward side of the yokes and serve in the same manner to lead back to the oil-chamber any oil that may find its way out between the forward face of the yokes and the rear face of the thrust-rings.

The operation of the apparatus may be briefly described as follows: Oil is supplied to the oil-chamber or compartment in the bearing-casing by any suitable means. This oil is pumped under a pressure into pipe 21, and when the pressure is sufficient to force the valves 42 from their seats oil will pass through the passages 44 to the pipes 18 and to the pressure-gages 54. From the pipes 18 the oil will pass into the ports 16 and thence to the delivery-ports 17. The valves 42 are so adjusted that in order to displace them the pressure in the pipe 21 must be greater than the pressure between the thrust-rings and the yokes. By maintaining such a pressure in said pipes and in their ports 16 and 17 a thin film of oil will be maintained between the thrust-rings and the rear sides of the yokes, and said film of oil or other lubricant will eliminate the friction between said parts. It will of course be understood that in order to secure this result the pressure on the oil must exceed the pressure of the thrust-rings against the yokes. As the oil finds its way from between the thrust-rings and the yokes it will be led back to the oil-compartment 2 by means of the guides 57 and 58.

The purpose of the controller 27 is to maintain an equal oil-pressure on the bearings, notwithstanding a variation in steam-pres-

sure. To this end the piston in the steam-cylinder is of much greater area than the piston in the oil-chamber, so that the pressure of the oil in the oil-chamber will be considerably greater than the steam-pressure on the piston 30. By this means a supply of oil is maintained under a heavy pressure in communication with the inlet-ports 43 of the casings 19. Should the pressure maintained by the pump be decreased—for instance, by reason of reduction in steam-pressure—the oil in the oil-chamber 29 would be forced downward by the steam above the piston 30 to compensate for the reduction in pressure maintained by the pump. The downward movement of the steam-piston would rock shaft 37 and open valve 41 through its connections 38 and 39, increasing the supply of steam to the pump, and thereby accelerating its movement and permitting it to raise the oil-pressure.

By the pressure-gages 54 the amount of pressure on the oil in the ports 16 and 17 may be instantly noted. Should one of said gages indicate a pressure much below that indicated by the others, it is at once apparent that its yoke is not fitting properly with the adjoining thrust-ring. This defect in adjustment may be easily corrected by the nuts 14.

Having thus described my invention, what I claim is—

1. A thrust-bearing comprising a shaft, a series of thrust rings or members thereon, a series of stationary rigid thrust-yokes adapted to take the thrust of the shaft, and means for maintaining oil under pressure between said yokes and the thrust members on the shaft, and means for indicating the pressure of said oil between each pair of thrust members.

2. A thrust-bearing comprising a shaft, a thrust member thereon, a stationary rigid thrust member to take the thrust of the shaft, means for maintaining oil under pressure between said thrust members, means for indicating the pressure on said oil, and steam-controlled means for governing the pressure on said oil.

3. A thrust-bearing comprising a bearing-casing formed with a lower oil-compartment, a shaft, a thrust-ring formed thereon and adapted to enter said oil-compartment, a stationary rigid thrust-yoke against which the thrust-ring is adapted to bear, oil-supply ports formed in said yoke and adapted to deliver oil between said yoke and the thrust-ring, means to direct the oil to the oil-compartment in the bearing, an oil-pump connected to said oil-compartment, means to deliver the oil from the pump to the ports in the yoke, and an automatic pressure-regulating valve interposed between the pump and the ports in the yoke.

4. A thrust-bearing comprising a bearing-

casing formed with a lower oil-compartment, a shaft, a thrust-ring formed thereon and adapted to enter said oil-compartment, a stationary rigid thrust-yoke against which the thrust-ring is adapted to bear, oil-supply ports formed in said yoke and adapted to deliver oil between said yoke and the thrust-ring, means to direct the oil to the oil-compartment in the bearing, an oil-pump connected to said oil-compartment, means to deliver the oil from the pump to the ports in the yoke, an automatic pressure-regulating valve interposed between the pump and the ports in the yoke, and a pressure-gage between said pressure-regulating valve and the ports in the yoke to indicate the oil-pressure in the ports.

5. A thrust-bearing comprising a bearing-casing formed with a lower oil-compartment, a shaft, a thrust-ring formed thereon a stationary rigid thrust-yoke against which the thrust-ring is adapted to bear, oil-supply ports formed in said yoke and adapted to deliver oil between said yoke and the thrust-ring, means to direct the oil to the oil-compartment in the bearing, an oil-pump connected to said oil-compartment, means to deliver the oil from the pump to the ports on the yoke, an automatic pressure-controlling valve between the pump and said ports, and oil-guards to catch the outward-flowing oil and direct it into the oil-compartment in the bearing-casing.

6. A thrust-bearing comprising a bearing-casing formed with a lower oil-compartment, a shaft, a thrust-ring formed thereon, a stationary rigid thrust-yoke against which the thrust-ring is adapted to bear, oil-supply ports formed in said yoke and adapted to deliver oil between said yoke and the thrust-ring, means to direct the oil to the oil-compartment in the bearing, an oil-pump connected to said oil-compartment, means to deliver the oil from the pump to the ports in the yoke, a steam-actuated pressure-controller connected to the oil-supply pipe, and means actuated by said pressure-controller to govern the pump.

7. A thrust-bearing comprising a bearing-casing, a shaft, a thrust-ring formed thereon, a stationary rigid thrust-yoke against which the thrust-ring is adapted to bear, oil-supply ports formed in said yoke and adapted to deliver oil between said yoke and the thrust-ring, an oil-pump connected to the ports in the yoke, a steam-actuated pressure-controller connected to the oil-supply pipe leading from the pump and consisting of an oil-compartment in communication with said supply-pipe, a steam-cylinder larger in diameter than the oil-compartment, a piston in the steam-cylinder, a piston in the oil-compartment, means connecting said pistons together, means to maintain a steam-supply above the piston in the steam-cylinder, and

means connected to the piston in the steam-cylinder to control the pump.

8. A thrust-bearing comprising means to maintain oil under pressure in the bearing, 5 and a pressure-controller consisting of an oil-compartment and a steam-compartment larger in diameter than the oil-compartment, a piston in each of said compartments, means for maintaining a steam-supply above the 10 piston in the steam-compartment, and means for delivering oil from the oil-compartment to the bearing, whereby the oil will be maintained under a pressure greater than the steam-pressure in the steam-cylinder.

15 9. A thrust-bearing comprising a suitable support, a shaft mounted therein, a series of thrust-rings on said shaft, a stationary rigid thrust-yoke for each of said thrust-rings and against which the thrust-rings are adapted to 20 bear, oil-supply ports being formed in said yokes and adapted to deliver oil between the yokes and the thrust-rings, an oil-pump to deliver oil under pressure to the ports in the yoke, an automatic pressure-controlling valve 25 for each thrust-yoke, said valve being interposed between the pump and the ports in the yoke, whereby an equal amount of oil will be delivered to the ports in each thrust-yoke.

10. A thrust-bearing comprising a support, 30 a shaft, a thrust member formed thereon, a stationary rigid thrust member, oil-supply ports formed in said stationary thrust member and adapted to deliver oil between said member and the thrust member on the shaft, 35 an oil-pump adapted to deliver oil under pressure to the port in the stationary thrust member, and an automatic pressure-regulating valve interposed between the pump and the ports in the stationary thrust member, where- 40 by the supply of oil to the thrust members will be stopped when the pressure is reduced below a predetermined point.

11. A thrust-bearing comprising a support, 45 a shaft, a thrust member formed thereon, a stationary rigid thrust member, oil-supply ports formed in said stationary thrust member and adapted to deliver oil between said member and the thrust member on the shaft, an oil-pump adapted to deliver oil under pres- 50 sure to the port in the stationary thrust member, and an automatic pressure-regulating valve interposed between the pump and the ports in the stationary thrust member, where- 55 by the supply of oil to the thrust members will be stopped when the pressure is reduced below a predetermined point, a pressure- 60 gage located between the pressure-regulating valve and the thrust members to indicate the pressure of oil in the ports of the stationary thrust member.

12. A thrust-bearing comprising a suitable support, a shaft mounted therein, a series of thrust-rings on said shaft, a stationary rigid thrust-yoke for each of said thrust-rings and 65 against which the thrust-rings are adapted to

bear, oil-supply ports being formed in said yokes and adapted to deliver oil between the yokes and the thrust-rings, an oil-pump to deliver oil under pressure to the ports in the yoke, an automatic pressure-controlling valve 70 for each thrust-yoke, said valve being interposed between the pump and the ports in the yoke, whereby an equal amount of oil will be delivered to the ports in each thrust-yoke, and a pressure-gage located between each 75 pressure-controlling valve and the ports in the thrust members to indicate the pressure of oil in said ports whereby the supply of oil to each pair of thrust members may be individually controlled and the pressure thereon 80 noted.

13. A thrust-bearing comprising a shaft, a thrust member thereon, a stationary rigid thrust member to take the thrust of the shaft, means for maintaining oil under pressure between said thrust members, and steam-controlled means for governing the pressure 85 on said oil.

14. A thrust-bearing comprising a shaft, a thrust member thereon, a stationary rigid thrust member to take the thrust of the shaft, means for maintaining oil under pressure between said thrust members, and steam-controlled means for governing the pressure 90 on said oil, and means actuated by said pressure-controller to govern the means for maintaining oil under pressure between the thrust members.

15. A thrust-bearing comprising a shaft, a thrust member thereon, a stationary thrust 100 member to take the thrust of the shaft, means for maintaining oil under pressure between said thrust members, steam-controlled means for governing the pressure on said oil, and an automatic pressure-controlling valve to regulate the supply of oil to the thrust members. 105

16. A thrust-bearing comprising a bearing-casing formed with a lower oil-compartment, a shaft extending through said casing, a plurality of thrust-rings formed on said shaft, a plurality of thrust-yokes fitting the spaces between said thrust-rings and adapted to be rigidly secured at their ends to the bearing-casing, said yokes being provided with oil-supply ports adapted to deliver oil 110 between the yokes and the thrust-rings, oil-guards connected to said yokes and bridging the joints between the yokes and the thrust-rings, said guards being adapted to direct oil 115 to the oil-compartment, an oil-pump, means to deliver oil from said pump to the ports in the yokes, an automatically-operating pressure-controlling valve for each thrust-yoke, and adapted to regulate the supply of oil to the ports in said yoke, and an independent 120 pressure-gage for each thrust-yoke and located between said thrust-yoke and the pressure-controlling valve to indicate the pressure of oil in said ports. 125

17. A thrust-bearing comprising a bear- 130

ing-casing formed with a lower oil-compartment, a shaft extending through said casing, a plurality of thrust-rings formed on said shaft, a plurality of thrust-yokes fitting the spaces between said thrust-rings and adapted to be rigidly secured at their ends to the bearing-casing, said yokes being provided with oil-supply ports adapted to deliver oil between the yokes and the thrust-rings, oil-guards connected to said yokes and bridging the joints between the yokes and the thrust-rings, said guards being adapted to direct the oil to the oil-compartment, an oil-pump, means to deliver oil from said pump to the ports in the yokes, an automatically-operating

pressure-controlling valve for each thrust-yoke and adapted to regulate the supply of oil to the ports of said yoke, and an independent pressure-gage for each thrust-yoke and located between said thrust-yoke and the pressure-controlling valve to indicate the pressure of oil in said ports, a steam-actuated pressure-controller connected to the oil-supply, and means actuated by said controller to govern the pump. 20
